WASHBOARD

Robert J. Aston, Pittsburgh, Pa.

Application May 26, 1936, Serial No. 81,907

1 Claim. (Cl. 68—231)

This invention relates to washboards and has for the primary object the provision of a device of this character having an improved scrubbing surface which will be efficient for the rubbing of the most delicate fabrics and without danger of injury or damage thereto and which may be sold at a low cost.

With these and other objects in view, this invention consists in certain novel features of construction, combination and arrangement of parts to be hereinafter more fully described and claimed.

For a complete understanding of my invention, reference is to be had to the following description and accompanying drawing, in which

Figure 1 is a front elevation, partly in section, illustrating a washboard constructed in accordance with my invention.

Figure 2 is a sectional view taken on the line 20 2—2 of Figure 1.

Figure 3 is a sectional view taken on the line 3—3 of Figure 1.

Figure 4 is a sectional view taken on the line 4—4 of Figure 3.

Figure 5 is a detail sectional view illustrating a modified form of my invention.

Referring in detail to the drawing, the numeral 1 indicates parallel legs of channel iron construction connected by a head construction 2 consisting of a rest 3 and a frame construction 4 fitting in the channel portions of the legs and having the latter secured thereto by nails or like fasteners 5. The frame portion 4 forms a rack in one face thereof for the reception of soap and other washing accessories. The rack is formed by cutting out a portion of the frame 4 and the cutout portion is closed by a backing 6 to which

may be secured a receptacle 7 in which the washing accessories may be positioned when desired.

A rubbing surface is constructed from a plurality of closely related cylindrical members 8 extending into the channels of the legs 1 and have adapted to their ends sleeves 9 and 9' acting as spacers to position the cylindrical members a desired distance apart. The sleeves 9' fit within the sleeves 9. The edges of the channels of the legs are bent inwardly, as shown at 10, and engage the spacers provided by the sleeves 9 and 9' and thereby secure the cylindrical members against displacement from the legs. The ends of the members 8 may be closed by caps 11 which will take the place of the sleeves 9 and 9', as 15 clearly shown in Figure 5.

Secured in the lower ends of the legs 1 and projecting therefrom are cushion feet 12. The lower portions of the legs are connected together by a plate or strip 13, the latter being secured in 20 the channels of the legs by fasteners 14. The cylindrical members 8 are free to rotate relative to the legs and present a very efficient rubbing surface over which delicate fabrics may be moved without danger of injury or damage thereto. 25

Having described the invention, I claim:

A washboard comprising a pair of metallic parallel channel legs, a head construction connecting said legs, a plurality of parallel cylindrical members extending into the channels of 30 the legs, and cylindrical spacers fitted on the ends of said members, said legs having the edges of the channelled portions bent inwardly to engage the spacers to thereby hold the spacers against inward movement relative to said members. 35

ROBERT J. ASTON.
